UNITED STATES PATENT OFFICE.

CHARLES W. GROENING, OF NEW YORK, N. Y.

RAILWAY-STATION INDICATOR.

1,152,725.

Specification of Letters Patent. Patented Sept. 7, 1915.

Application filed July 7, 1914. Serial No. 849,408.

To all whom it may concern:

Be it known that I, CHARLES W. GROENING, a citizen of the United States, and a resident of the city of New York, borough 5 of Brooklyn, in the county of Kings and State of New York, have invented a new and Improved Railway - Station Indicator, of which the following is a full, clear, and exact description.

10. Among the principal objects which the present invention has in view are: to provide means for displaying the names of successive stations, said means incorporating operating devices disposed in successive arrangement to the stations of a railway system; to provide means for adjusting the medium on which the names of the stations are placed to register with the structural peculiarities of the roadbed; to provide a simple 15 and efficient means for reversing the feed of an announcement ribbon with which the indicator is provided; to provide means for insuring the effective engagement of the ribbon-shifting device and the roadbed device; and to simplify the mechanism constituting the indicator.
20. vice; and to simplify the mechanism constituting the indicator.
25. *Drawings.*—Figure 1 is a vertical cross section of a car body, showing an indicator and operating mechanism therefor constructed and arranged in accordance with the present invention; the car body and transmission parts of said mechanism being broken and condensed; Fig. 2 is a vertical section on an enlarged scale, taken on the line 2—2 in Fig. 1; Fig. 3 is a vertical section on an enlarged scale, taken on the line 3—3 in Fig. 1; Fig. 4 is a detail view on an enlarged scale, showing the face of the indicator as disposed in service; Fig. 5 is a side 30 view of the brake-liberating and driving-pulley-actuating mechanism, the view being taken from the position designated by the numeral 5 in Fig. 1; Fig. 6 is a detail view on an enlarged scale, taken on the line 6—6 in Fig. 1; Fig. 7 is a top plan view of a track-bed-actuating device; Fig. 8 is a detail view in perspective, showing the adjusting mechanism with which the indicator is provided 35 for reversely operating the indicator mechanism.

Description.—In the embodiment of the present invention shown in the drawings, a ribbon 15 is employed. The ribbon 15 has 40 imprinted thereon, at regular intervals, names or indications of the stations with

which the railway is provided. The feeding mechanism for said ribbon is controlled to correspond with the location of the station relative to the route of travel, and in relation to the terminals of the railway system or branch thereof. In the present embodiment, the differentiation in the extent of the feeding mechanism is directly affected by variations in length of yielding friction rails 45 16, with which the roadbed is equipped. The length of each particular rail 16 is determined by the location of the station in relation to the length of the roadbed. To support each of the rails 16, they are provided with plungers 17, which rest on springs 18 in uprights 19. The uprights 19 are preferably provided with wide flanges 20, by which they are rigidly secured on a base 21 formed of any suitable material and by any 50 suitable method. Supported on the same base 21 are rigid releasing rails 22, said rails being supported on standards 23, as best shown in Fig. 5 of the drawings.

When a railway system is equipped with 55 the present invention, each vehicle is provided with a friction pulley 24 guided in brackets 25 which are bolted or otherwise secured to the under framing of the vehicle. The brackets 25 are arranged in pairs, the 60 members of each of which are spaced apart, and formed each integral with a bolting flange 26. The adjacent faces of the brackets 25 are grooved to hold in guided relation the side bars of a bearing yoke 27. The yoke 27 is adjustable vertically in the brackets 25, being to this end provided with a tapped perforation to receive a suspension screw 28 which has a flat head 29 that rests within a chamber formed in a socket fixture 30, likewise bolted or rigidly secured to the under framing of the vehicle. The main purpose of the construction embodying the yoke 27 and screw 28 is to adjust or regulate the 65 working position of the pulley 24. To facilitate the adjustment, the screw 28 is provided with a wrench nut 31, between which and the top member of the yoke 27 a coiled spring 32 is disposed.

The yoke 27, at the lower extremity thereof, provides bearings for a shaft 33. The shaft 33 has fixedly mounted thereon the pulley 24 and a bevel gear wheel 34. The gear wheel 34 engages a companion gear wheel 35, which is fixedly mounted, at the lower end, on a short transmission shaft 36 having bearings in brackets 37 extending

from the side of the yoke 27. At the upper end of the shaft 36, a bevel wheel 38 is slidably mounted, and is provided with a set screw 39 in the hub thereof to facilitate the setting of the wheel 38 in an adjusted position on the shaft 36. The yoke 27, shafts 33 and 36, and parts connected therewith and mounted thereon are adjusted vertically in one and the same operation and by manipulating the nut 31. In this manner, the operative position of the pulley 24 with reference to the rails 16 is adjusted to suit the structural conditions of the various vehicles to which the indicator is applied.

15 When the adjustment has been effected, the wheel 38 is moved into mesh with the bevel gear wheel 40, and the set screw 39 tightened to hold the wheel 38 in its operative relation. Thereafter, when the vehicle 20 is moved over the roadbed, the pulleys 24 on said vehicle will engage the rails 16, depressing the same sufficiently to cause the springs 18 to exert gripping pressure on said rails to rotate the pulley 24 while the same 25 is passing over said rails.

To prevent the rotation of the pulley 24 intermediate the stations and the rails 16, a brake-shoe 41 is provided to grip in holding relation each of the pulleys 24. For this 30 purpose, the shoes are provided with a goose-neck rod 42, which is guided in a bearing formed in boxes 43, said boxes being permanently secured to the brackets 25, as seen best in Fig. 1 of the drawings. At the 35 lower end of each rod 42, a shoe 44 is mounted to engage and ride upward on the various rails 22. To this end, the shoes 44 are curved on the lower edge, as best seen in Fig. 6 of the drawings, and the engaging 40 end 45 of each rail 22 is dipped to form an upward-riding cam surface.

To maintain a gripping pressure of the 45 brake-shoe 41 on the pulley 24, a spring 46 is provided. The spring 46 infolds the rod 42 to spread between the boxes 43 and the suspension plate 47 to which the rod 42 is rigidly secured at the lower end thereof. The 50 rod 42, conjointly with a vertical slot formed in the shoe 44, through which slot passes the shaft 33, guides said shoe in its movement when lifted by the rails 22.

In the normal arrangement of the pulleys 24 and the shoe 44 in each installation, the shoe 44 extends below the pulley 24, as seen 55 best in Fig. 5 of the drawings. The extent to which the shoe 44 projects below the pulley 24 determines the lift of the brake-shoe 41 from the pulley 24 prior to the engagement of said pulley with a rail 16. As 60 will be seen best in Fig. 7 of the drawings, each of the ends 45 on the rails 22 is advanced beyond the engaging end of the rail 16, thereby affording the necessary time for the lift of the shoes 44 and 41 to free the pulley 24. It will also be noticed that the

70 delivery ends of the rails 16 register with the delivery ends of the rails 22, thus insuring the instant setting of the brake-shoe 41 on the pulley 24 at the moment the pulley 24 leaves each rail 16.

The arrangement of the rails 16 and 22 shown in Figs. 1 and 7 of the drawings is that employed on what may be termed a "single-track" roadbed, or for tracks where the traffic is in both directions. Also, it will 75 be understood that in equipping a roadbed, a rail 16 and its corresponding rail 22 are disposed on the roadbed adjacent to a station, and preferably on the leaving side thereof. In cases where the roadbed is arranged for single traffic, it probably would be best arranged to have the single rail 16 and the double rails 22 at the station. In the last-mentioned arrangement, it would 80 need to be understood that the indicated station was the next succeeding station. It will also be understood that as the gathering roll of the ribbon 15 is gradually increased, the length of the rails 16 is gradually decreased, thus compensating for the increased 85 feed of the ribbon roll by the decreased extent of the driving mechanism therefor. In this manner, the regular disposition of the station indications is preserved.

The ribbon 15 is removably mounted, and 90 the opposite ends are secured to spools 48 and 49. The spools 48 and 49 have guide flanges 50. At one end of each spool is a round bearing pintle 51, to receive which a bearing cup 52 is provided. At the opposite 100 end of each spool, a pintle 53 is provided, through which a pin 54 extends, said pin resting in radial slots in cups 55. A cup 55 is provided on each of the short shafts having each a bevel gear wheel 56. Each of the 105 shafts is also mounted in bearings formed in a partition 57 of an indicator case 69, as shown best in Fig. 1 of the drawings.

The spools 48 and 49 are held in operative 110 relation, so that the pintle 53 and pin 54 thereof are maintained in the cups 55 by springs 58, which springs infold spindle shanks with which the cups 52 are provided, said spindles being further furnished with flat heads 59, which heads move in cups 60. 115 The spools 48 and 49 are driven alternately, selection depending on the engagement of the wheels 56 by one or other of the bevel gears 61 or 62. The shaft 63 on which said gears 61 and 62 are mounted is reversely rotated in correspondence with the feed of the spool 48 or 49, the feed of which is relatively reversed. The reversion referred to 120 of the shaft 63 is incident to the engagement of a bevel gear wheel 64 by bevel gear wheels 65 or 66, as the case may be. The gear wheels 65 and 66 are shifted relative to the gear wheel 64 by means of the shaft 63 on which the wheels 65 and 66 are mounted. The shaft 63 is slidably mounted in a socket 125 130

- 67, wherein is disposed a spring 68, the function whereof is to normally move the shaft 63 toward the lower portion or bottom of the case 69. A spacing block 70 is provided 5 for supporting said shaft. The block 70 has two thicknesses, the thinner portion 71 serving to support the shafts 63 in a neutral position, or a position wherein both the wheels 65 and 66 are disengaged from the wheel 64.
- 10 When the pointed end of the shaft 63 is supported on the thicker portion of the block 70, the wheel 66 is operatively engaged with the wheel 64, as best shown in Figs. 1 and 3 of the drawings. When the block 70 is removed 15 from the path of the shaft 63, and the end 72 thereof rests on the bottom of the case 69, the wheel 65 is engaged with the wheel 64.
- To assist in shifting the block 70, said 20 block is mounted on angle rails 73, and is provided with a handle knob 74. To relieve the block 70 of the weight of the shaft 63 and parts connected therewith during the operation of shifting said block, a lever yoke 25 75 is provided, which lever yoke is pivoted by means of a shaft 76 at the rear of the case 69. The side bars of the yoke 75 are connected by a handle bridge 77. The side bars of the yoke 75, when raised, engage a 30 wheel 78, to lift the shaft 63. The block 70 is shifted to alter the feed of the ribbon 15 usually at the end of the run of the vehicle which is equipped with the herein-described indicator. To do this, the operator opens 35 the door 85, and, grasping the handle 77 of the yoke 75, raises the same until it engages the wheel 78. A further lift of the yoke 75 releases the block 70, which may be then shifted to suit the arrangement wished for.
- 40 If the adjustment of the ribbon 15 is at this time that which is desired, the shift is from the thickened portion of the block 70 to the bottom of the case 69; or, vice versa. If, however, the ribbon 15 needs adjusting, for 45 correction or to suit a change in purpose, the shaft 63 is allowed to rest on the thinner portion 71 of said block, when, the wheel 64 being disengaged, the shaft 63 and parts connected therewith may be revolved at will.
- 50 To shift the spools 48 and 49 independently of the shaft 63, the bevel gear wheels 80 and 81 are provided, said gear wheels being in mesh with the wheels 56 connected with the spools 48 and 49, respectively. The 55 shafts 82 and 83 upon which the wheels 80 and 81, respectively, are mounted are journaled in framing members 84 of the case 69, and extend between the partitions 57 and the adjacent side of said case. The partition 57 60 forms, with said case, a compartment 86, to which access is gained through a door 85. When the door 85 is thrown back, crank handles 87 are exposed in position to be engaged by the operator.
- 65 It is obvious that when the shaft 63 is so disposed as to release the wheel 64 from engagement with the wheels 65 and 66, either of the crank handles 87 may be manipulated to wind the spools 48 and 49, thus adjusting the ribbon 15 thereon to altered or new 70 working conditions.
- The wheel 64 is driven in timed relation to the wheel 38 through the wheel 40, a transmission shaft 88, miter wheels 89, a transmission shaft 90, miter wheels 91, and 75 a shaft 92. If it is desired to reduce the speed of rotation between the shaft 33 and the spools 48 and 49, this may be readily accomplished by proportioning any of the various wheels forming the transmission 80 above traced. By so doing, the proportionate amounts of travel of the ribbon 15 may be reduced or increased to suit various operating conditions. Under all conditions, the ribbon is shifted between stations, and 85 preferably at a point adjacent the station just passed. The name or index of the coming station will be shown through the view opening covered by glass panels 93. The panels 93 are disposed at the inner end of 90 inset passages 94. These passages open from the center of the case 69 in both directions, and the ribbon 15 is provided with imprinted names or indexes of similar purport, on both sides thereof, to be read through both 95 passages 94 from either end of the vehicle when, as preferred, the case 69 is suspended from the roof of the vehicle by means of posts 95 disposed midway of the vehicle. To guide the ribbon, rotatively-mounted 100 rods 96 are disposed as shown, to hold a small section of the ribbon in line with slotted guide plates 97, as seen best in Fig. 1 of the drawings.
- 105 It will be understood that the ribbons 15 are removably attached to the spools 48 and 49. It will also be understood that the spools may be removed from the case 69, the operation needed for this purpose being to press each of the spools backward, compressing the springs 58, until the pintles 53 pass out of engagement with the cups 55. The mounting of the pintles 51 in the cups 52 is sufficiently easy or free to permit the spools to be swayed to one side so that the pintles 53 will avoid the cups 55 when drawn in that direction. The spools may in this manner be removed from the case 69.
- 110 To avoid the possibility of the pulley 24 refusing to revolve while passing over the rail 16, a gear wheel 98 is fixedly mounted on the side of the pulley 24, the teeth whereof slightly project beyond the periphery of said pulley to engage the teeth of rack sections 99, with which the rails 16 are provided, as best seen in Fig. 7 of the drawings. The rack sections 99 are disposed on the opposite edges of said rails, and are set back from the entrance end thereof to permit the rails 16 to start the pulley rolling, 115 120 125 130

if frictional grip of the rails is sufficient for that purpose. Should, however, the grip be insufficient to start said pulley rolling, the teeth of the wheel 98 engaging the teeth of the rack section 99 will insure the rotation of said pulley.

Claims:

1. A railway station indicator, comprising a movable index having display members serially arranged; means for successively exposing said members, embodying an actuating device disposed adjacent the roadbed; and a plurality of operating devices serially mounted on the roadbed for operatively engaging said actuating device, said operating devices being graduated to operate in correspondence with the serial arrangement thereof.
2. A railway station indicator, comprising a movable index having the names of stations serially arranged; an operating mechanism for successively exposing said names, said mechanism embodying a rotary member disposed adjacent the roadbed; a plurality of operating rails for engaging said rotary member for relatively short periods, in correspondence with the time requirement for exposing said names; resilient supports for said rails to maintain the same normally in the path of said rotary member; a brake

for said rotary member; means for automatically setting said brake to hold said rotary member; and means mounted upon the roadbed for releasing said brake prior to the engagement of said rotary member with said rails.

3. A railway station indicator, comprising a movable index having the names of stations serially arranged; and operating mechanism for successively exposing said name, said mechanism embodying a rotary member disposed adjacent the roadbed; a plurality of operating rails for engaging said rotary member for relatively short periods, in correspondence with the time requirement for exposing said names; resilient supports for said rails to maintain the same normally in the path of said rotary member; a brake for said rotary member; means for automatically setting said brake to hold said rotary member; and a plurality of releasing rails disposed intermediate the stations of a railway system.

In testimony whereof I have signed my name to this specification in the presence of two subscribing witnesses.

CHARLES W. GROENING.
